John R. Whittemore

UNITED STATES PATENT OFFICE.

JOHN R. WHITTEMORE, OF CHICOPEE FALLS, MASSACHUSETTS.

IMPROVEMENT IN LIFTING-JACKS.

Specification forming part of Letters Patent No. **157,663**, dated December 8, 1874; application filed May 18, 1874.

To all whom it may concern:

Be it known that I, JOHN R. WHITTEMORE, of Chicopee Falls, Hampden county, Massachusetts, have invented certain new and useful Improvements in Lifting-Jacks; and do hereby declare that the following is a full, clear, and exact description thereof, reference being had to the accompanying drawings making a part of this specification, in which—

Figure 1 represents a side view with one side of the standard broken away at the top. Fig. 2 represents a front view, and Fig. 3 a view of the catch which holds the lever in place.

My invention relates to that class of lifting-jacks in which a notched lifter is moved up and down upon a standard; and the nature of my invention consists in a notched lifter provided with vertical grooves on its sides, into which grooves fit flanged studs, which are secured to the front of the standard, the said lifter being provided with a rack-bar, into which works the segmental end of a lever, all as more fully hereinafter set forth.

A represents a standard, rested upon a base, and having an open mortise at the top, into which is pivoted a lever, C, having a segment at its end provided with cog-teeth. Upon the front of the standard are four flanged studs, F F F F, which are secured apart from each other by the screws G. B represents the lifter, which is inclined rearward at the upper part, and having notches *b* in stair-step form, so that the top thereof extends over the top of the standard, while the lower part of the same rests against the front of the standard. The

straight portion of this lifter has a groove, H, on each side, and into these grooves the flanges on the studs F enter to hold it to the standard and allow it to be moved freely up or down. The part of this lifter nearest the standard has cog-teeth I, into which the teeth on the segmental end of the lever take, and cause the lifter to rise or fall as the lever is worked. D represents a catch, which is made of sheet metal, in the form seen in Fig. 3, and is attached to the standard A in an inclined position, as seen in Fig. 1, so that the lifter may be held at any height desired by catching the lever against the same. The lifter is perfectly guided in its up-and-down movements by means of the grooves therein and the flanged studs.

Whenever it is necessary to remove the lifter it is only necessary to loosen two of the flanged studs on the same side, turn them on the screws, and lift out the lifter B from the two unloosened studs.

I do not claim a lifting-jack in which an inclined notched lifter slides on a standard, and is operated by means of a segment acting upon a swinging rack-bar on the exterior of the lifter, as I am aware that such is now new.

What I claim is—

The combination, with the standard A, of the flanged studs F F and the lifter B, having vertical grooves H on its sides, all substantially as set forth.

JOHN R. WHITTEMORE. [L. S.]
